WIRE BEAMER TENSIONER UNIT AND
METHOD

Robert C. Pierce, Niles, Mich., assignor to National-Standard Company, a corporation of Michigan

Application July 18, 1940, Serial No. 346,235

10 Claims. (Cl. 242—25)

This invention relates to improvements in wire beamer tensioner unit or wire winding apparatus and method. The invention is more particularly applicable to apparatus and method for winding a plurality of wires in a set.

In connection with the manufacture of rubber vehicle tires and for other purposes, it is frequently desirable to provide a plurality of relatively fine flexible wires in a set. For example, as here shown, such a set may include four separate wires. At each end of the set, the separate ends of the individual wires are ordinarily fastened together in some suitable manner to facilitate handling of the set or group of wires. For shipping purposes, the set is usually wound upon an ordinary spool or drum.

My invention relates more particularly to apparatus and method for winding such a set of wires upon a spool. In ordinary practice, the set is formed as it is wound upon the spool by drawing separate wires from separate supply spools and winding them together in a set upon the new spool. In the present specification I shall assume, merely for purpose of example, that the set includes four wires. It is to be understood, however, that such a set may comprise any number of wires. In former practice, the ends of the four wires were initially joined together to start the set, and then the four wires together were wound upon the spool, each wire freely flowing from each separate spool. In such practice, it usually happened that the individual wires of the set would not wind evenly on the receiving spool with the result that some wires of the set would be longer than others. In winding on the receiving spool some wires of the set would ride up on others, while some would drop down between, so that during the winding operation some wires of the set would be drawn more rapidly from the supply spools than others. As stated, the result of this was to place upon the receiving spool a set of wires of uneven lengths. Consequently, when the set was removed from the spool, difficulty was encountered because some wires of the set were longer than others.

The principal feature of my invention is the provision of apparatus and method for winding such a set of wires upon a spool so that all the wires of the completed set, after being wound upon the spool, will be of the same length. When such a set is removed from the spool, all the wires will lie parallel under equal tension and be adapted for ready application in manufacture.

In general, it may be stated that my invention comprises, in combination with a spool winding 55

thereon a plurality of wires in a set, means for positively feeding to said spool each individual wire of the set at the same rate. In the former practice, the receiving spool would draw each individual wire of the set freely from the supply spool. If one wire of the set ran up on high places on the receiving spool that wire would be drawn just that much faster from its supply spool with the result that that wire of the set 5 would be longer than the others. The essence of my invention is to prevent this by definite feeding, measuring or metering each separate wire of the set so that they all will positively be fed to the receiving spool at the same rate. 10 In the practice of my invention, each wire of the set is supplied from an individual supply spool, but there is interposed between the supply spools and the set receiving spool, apparatus which definitely measures, meters, or feeds the 15 separate wires all at the same rate. In general, this comprises two large drums around which the four wires are wound several times so as to have sufficient frictional engagement with said drums to prevent slippage of any wire. To increase 20 the frictional engagement there are smaller friction drums pressing against the wires to hold them in contact with the larger drums. The set receiving spool pulls the set to drive these drums, and the wires are supplied to the drums from the 25 four individual supply spools. With this construction, the wire or wires having the greatest tension between the receiving spool and the friction drums will drive the latter at a certain rate. If any wire of the set, however, is dropping 30 in low places, such as valleys or depressions between wires previously wound on the receiving spool so that its tension is decreased, it will become temporarily slack between the receiving spool and the friction drums. Such friction 35 drums, however, will continue to feed it at the same rate as the wire having the greatest tension. The result of this slackness will be to cause this wire to ride up on the higher places on the receiving spool until finally such slackness 40 is taken up. In other words, the slackness will facilitate the more rapid taking up of this slack wire on the receiving spool, while the wires with greater tension will tend to be pulled down into low places, such as valleys or depressions 45 between the wires previously wound on the receiving spool, with the result that the slack wires will be taken up more rapidly and the taut wires 50 not so rapidly, with the final result that the individual wires of the complete set upon the receiving spool when the winding is completed will

all be of the same length within exceedingly fine limits.

In that form of device embodying the features of my invention shown in the accompanying drawings, Fig. 1 is a view in side elevation, Fig. 2 is a view in end elevation, Fig. 3 is a view, taken as indicated by the line 3 of Fig. 1, Fig. 4 is a top plan view, and Fig. 5 is a view in side elevation on a reduced scale.

As shown in the drawings, 10a, 11a, 12a, and 13a indicate four separate supply spools for supplying the four wires 10, 11, 12, and 13, respectively, to form the set to be wound upon the set receiving spool 14 which is driven in any suitable manner (not shown).

15 indicates a suitable spreader of well known construction adapted for reciprocal movement to move the wires back and forth as they are being wound upon the spool 14 in order to distribute them more or less evenly on the spool in a well known manner.

Located between the set receiving spool 14 and the supply spools are the two friction drums 16 and 17 about which the set of wires is wound four times, as shown in the drawings. 18 indicates a comb, between the teeth of which the wires are placed in order to assist in holding them in separated positions. The drums 16 and 17 are sufficiently large and are made of suitable material so that the wires frictionally engage the same with substantially no slippage thereon. This frictional engagement is increased by the pressure of two additional friction rolls 16a and 17a, above the drums operating by gravity, and weighted, as desired, to press the wires more securely into frictional engagement with the drums 16 and 17.

The drums 16 and 17 are driven by the spool 14 through the tension of one or more of the wires. Suitable drags or friction devices (not shown) for the supply spools are provided to prevent overrunning of the same.

As shown in Fig. 5, there is some space between the spool 14 and the friction drums 16 and 17. It will be seen that the wire or wires that are wound fastest upon the spool 14 will have the greatest tension between the spool 14 and friction drums 16 and 17, and consequently will be the wires driving such friction drums. For example, as shown in Fig. 5, I have indicated one of the wires 10 as having greater tension than the wire 13. This drawing is largely diagrammatic and the other two wires for convenience are not shown. The principle can just as well be illustrated with two wires. As shown in this figure, the wire 10, having gone up on the high places on the spool 14, has had its tension increased. Since all the wires are frictionally in engagement with the drums 16 and 17, said drums have fed the wire 13 just as fast as the wire 10. Since the wire 13 has gone into low places on the receiving spool and consequently not been taken up as fast, it has developed some slack between the spool 14 and the friction drums. The result of this condition is to cause the taut wire 10 to be pulled down into the low places on the spool. That is, this wire is not so likely to ride up on other wires on the spool. The wire 13 being slack, however, will ride up on the higher places, or because of its slackness will be taken up faster by the spool 14. The result will be to equalize the differences in tension of the wires 10 and 13. Stating the matter in more simple and general words, it can be said that as soon as any wire becomes more taut than the others, it will

not be taken up by the spool so rapidly; and as soon as any wire becomes more slack than the others, it will be taken up more rapidly. The result of this is a continual tendency to equalize the tension and winding rate of the individual wires of the set with the result that all the wires of the set, as finally wound upon the spool, will be of practically the same length.

It is to be understood that there is sufficient drag (not shown) on the friction drums to cause sufficient tension on one or more of the wires through which the drums are driven from the winding spool to accomplish the objects of the invention.

15 My invention finds particular use in connection with braiding machines making tubular braid. Anywhere from 2 to 35 wires or more may be wound on a beamed spool with my improved apparatus and one spool is mounted on each carrier of the braiding machine. For example, there may be a 24 carrier circular braider with 10 wires on each spool in each carrier. In such case, if the wire is soft and easily stretched, the tighter ones may do so and thus all the wires may come to a uniform length; but in stronger materials such as high carbon wires, phosphor bronze and the like the wire does not stretch so easily and if unevenly wound on the spool there are likely to be loops at the braiding point which cause flaws in the braiding. By the use of my invention the wires may all be wound on the spool at a given length thus facilitating the making of commercially smooth tubular braid.

The foregoing detailed description has been given for clearness of understanding only, and no unnecessary limitations should be understood therefrom for some modifications will be obvious to those skilled in the art.

I claim:

1. In combination with a spool winding thereon a plurality of wires in a set, means for positively and simultaneously feeding to said spool each individual wire of the set at the same rate.
2. In combination with a spool winding thereon a plurality of wires in a set, means for positively and simultaneously feeding to said spool each individual wire of the set at the same rate, said means including a drum about which the wires are frictionally wound.
3. In combination with a driven spool winding thereon a plurality of wires in a set, means for positively and simultaneously feeding to said spool each individual wire of the set at the same rate, said means being driven from said spool by said wires.
4. In combination with a driven spool winding thereon a plurality of wires in a set, means for positively and simultaneously feeding to said spool each individual wire of the set at the same rate, said means including a drum about which the wires are frictionally wound, said drum being driven from said spool by said wires.
5. The method of winding a plurality of wires in a set upon a spool comprising positively and simultaneously feeding to said spool each individual wire of the set at the same rate.
6. In the winding of a plurality of wires in a set upon a spool, the method of causing the wire winding most rapidly thereon positively and simultaneously to feed to said spool the other wires of the set at the same rate.
7. In combination with a driven spool winding thereon a plurality of wires in a set, means driven by said spool through the wire winding most rapidly thereon, said means operating si-

multaneously to feed to the spool the remaining wires of the set at the same rate.

8. In combination with a driven spool winding thereon a plurality of wires in a set, means driven by said spool through the wire winding most rapidly thereon, said means operating through frictional engagement with the remaining wires simultaneously to feed to the spool said remaining wires of the set at the same rate.

9. The method of producing a set of wires of equal length by a single winding upon a driven spool which comprises simultaneously presenting to the spool individual wires of the number in the set from a metering device and maintain-

ing each wire in presentment relationship to the spool whereby inequalities in take-up of the individual wires are overcome by adjustment upon the spool.

5 10. The method of producing a set of wires of equal length by a single winding upon a driven spool which comprises simultaneously presenting to the spool individual wires of the number in the set from a metering device driven by said wires and maintaining each wire in presentment relationship to the spool whereby inequalities in take-up of the individual wires are overcome by adjustment upon the spool.

ROBERT C. PIERCE.
